A. F. JACKSON.

SPOON OR FORK HANDLE.

No. 18,490.

Patented July 31, 1888.

Fig. 1

Fig. 2

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A SPOON OR FORK HANDLE.

SPECIFICATION forming part of Design No. 18,490, dated July 31, 1888.

Application filed June 15, 1888. Serial No. 277,271. Term of patent 7 years.

To all whom it may concern:

Be it known that I, AUSTIN F. JACKSON, a citizen of Great Britain, residing at Taunton, in the county of Bristol and State of Massachusetts, have invented and produced a new and original Design for Spoon or Fork Handles, of which the following is a specification, reference being had to the accompanying drawings, forming a part thereof, in which—

10 Figure 1 is a front view, and Fig. 2 a back view, of a spoon having its handle ornamented according to my design.

The leading feature of my design consists in the representation on the face of the handle of narrow strip-like panels A, extending diagonally across the face of said handle, those nearest the narrow or bowl end of the handle being of less width than the upper panels, the representation of a leaf-like spray, B, being produced at the end of the lower panel, the panels serving to give the handle the appearance of being twisted. At its upper end the upper panel extends at α in a narrowed portion along the face of the handle next its edge nearly to the center of the upper end of said face, where it meets a scroll-like center ornament, C, from the opposite side of which extends an ornamentation, D, producing a bead-like effect. In the space at F, above the upper strip panel,

there is presented the representation of a leafy spray, F'. The representation of a spray, f, is also produced on one of the intermediate ones of the strip-like panels A.

On the rear side of the handle, at its upper end, is produced centrally a scroll-like ornament, G, from the opposite sides of which the representations of leafy sprays H extend for a short distance, as shown, down along the edges of the handle.

Lines I curve inwardly across the back of the handle, an ornament, J, being produced above such lines, and the representation of a leafy spray being produced below the same, as shown.

What I claim is—

1. The design for the front side or face of handles of spoons or forks, substantially as shown and described.
2. The design for the rear side of the handles of spoons or forks, substantially as shown and described.
3. The design for the ornamentation of the handles of spoons or forks, substantially as shown and described.

AUSTIN F. JACKSON.
